United States Patent Office

Des. 192,463
Patented Mar. 27, 1962

192,463

CAP

Lillian Gettinger, Baltimore, Md., assignor to André Fantasies, Inc., a corporation of Maryland

Original application Aug. 26, 1960, Ser. No. 61,907, now Des. Patent No. 190,717, dated June 27, 1961. Divided and this application June 19, 1961, Ser. No. 66,641

Term of patent 14 years

(Cl. D3—13)

FIG. 1

This application is a division of my co-pending application Serial No. D. 61,907.

I claim:

The ornamental design for a cap, substantially as shown.
